CLAIM

The ornamental design for a shoe, as shown and described.

DESCRIPTION

FIG. 1 is a front perspective view of a shoe showing my new design;

FIG. 2 is a bottom view thereof; and,

FIG. 3 is a rear perspective view thereof.

The broken lines showing the interiors of the outsole elements and the unshaded regions therein form no part of the claimed design. The broken lines depicting the remainder of the shoe show features that form no part of the claimed design.
